WINDOW SHADE BRACKET FIXTURE

Filed March 11, 1929

UNITED STATES PATENT OFFICE

DUANE A. PARKES, OF DETROIT, MICHIGAN

WINDOW SHADE BRACKET-FIXTURE

Application filed March 11, 1929. Serial No. 346,084.

My invention relates to brackets for supporting window shades shown in the accompanying drawings and more particularly described in the following specification and 5 claim.

The primary object of the invention is to provide a bracket fixture of such construction that a window shade roller may be readily installed or removed from the brackets,— 10 but when supported by the brackets, cannot be accidentally detached from the fixture to damage the curtain or injure anyone beneath it.

Another object of the invention is to provide an inconspicuous device that may be attached to a window stop in such manner that the edges of the window shade are adjacent the window casing, thereby cutting off light which might otherwise pass between the edge 20 of the shade and the window casing.

A further object of the invention is to construct one or both of the brackets of resilient material that one at least may be manually shifted from its normal spaced relation to 25 the other bracket to permit the projecting gudgeons at the ends of the shade roller entering the apertures provided in the respective brackets;—the bracket being then released, that it may spring back to its initial 30 position, thus engaging the gudgeons until forced again from its normal position for the removal or replacement of a shade.

A further object of this invention is to provide a bracket fixture whereby the 35 gudgeons on the end of the roller cannot jump out of the supporting hanger or bracket through careless handling of the shade.

With the foregoing and other objects in view which will appear as the description 40 proceeds, the invention further resides in the combination and arrangement of parts and in the details of construction hereinafter described and claimed, it being understood that changes may be made in the precise embodiment of the invention herein disclosed 45 without departing from the spirit of the same.

In the drawings accompanying this specification:

Figure 1 is a perspective view of the

bracket fixture supporting a window shade,— shown partly broken away and in section.

Figure 2 is a side view of one of the brackets attached initially to the window stop by a single nail, that the brackets may be first 55 adjusted as indicated by dotted lines, to properly align the curtain roller before permanently securing the brackets to the window stop.

Figure 3 is an elevation of the co-operating 60 bracket provided with a squared aperture to receive the usual rectangular supporting gudgeon at the opposite end of the shade roller.

Figure 4 is a sectional view taken on or 65 about line 4—4 of Figure 2.

The respective brackets A and B forming the shade roller supporting fixture are constructed of sheet metal. The bracket A includes an elongated portion A¹, perforated 70 with a plurality of holes A², to receive nails A³, whereby it may be temporarily, and afterward permanently secured to the window stop.

The bracket A, has also a laterally extending portion A^b, punched with a round hole A^c to receive the usual round gudgeon (not shown) at one end of a shade roller C. 75

The laterally extending portion A^b is bent midway its length, to form a shallow channel 80 A^d, thereby spacing the fixture from the edge of the shade that the edge of the latter may not be worn through contact with the bracket when raised or lowered.

Integral with the bracket and projecting 85 downwardly from the end of the laterally extending portion A^b is an arm A^e,—its lower end being bent outwardly at an angle to provide a grip or thrust portion A^f, for the fingers of the person when manipulating 90 the bracket to release the shade roller from the support of the fixtures or when engaging it therewith.

The coordinating bracket B, has an elongated portion B¹ punched with a plurality of holes B² for the passage of supporting nails (not shown) to secure the bracket to the window stop. 95

A single nail is first driven through the hole in the center of the bracket to tempo- 99

rarily secure it to the window stop;—an adjustment of the brackets then follows to obtain a proper alignment of the shade roller, the brackets are then permanently secured to the window stop by additional nails.

• The bracket B also includes a laterally extending arm formed with a shallow channel B^a for spacing the fixture from the edge of the shade that the edge of the latter may not be worn through contact with the fixture when raised or lowered.

Adjacent the end of the arm is an elongated aperture B^c to receive the usual square gudgeon attached to the winding spring of the shade roller.

A relatively broad bearing surface *a* surrounds the opening A^c in the bracket fixture—see Figure 4—to receive and support the gudgeon of the shade roller.

Having indicated the several parts by reference letters, the construction and operation of the device will be readily understood.

The respective brackets A and B are first secured to the left and right hand window stops, adjacent the top of the window casing, by a single nail preferably driven through the centrally disposed nail aperture of a group of holes provided to receive nails in each of the brackets.

Pressure is then manually applied to the end portion A⁴ of the bracket, forcing the latter toward the window casing to permit the gudgeons projecting in opposite directions from the ends of the shade roller to be inserted in the respective holes, or bearings provided for their reception in each of the brackets. The end A⁴ of the resilient bracket is then released that it may return to its initial position, thereby securely engaging the roller gudgeons against accidental release.

The brackets are now rocked upon the supporting nails driven through each bracket into the window stops,—see Figure 2—until a proper alignment of the shade roller has been effected, whereupon additional nails are driven through the holes to permanently secure the brackets in their adjusted position.

It will be noted that the bearings in both brackets completely encircle the gudgeons,—the usual hook-shaped bearing employed in curtain brackets being eliminated,—this taken in connection with the resilient action of the brackets avoids any possibility of the curtain roller leaving the brackets through carelessness in raising or lowering the shade.

Having thus described my invention, what I claim is:

30 A window shade bracket consisting of an elongated base portion adapted to be secured to a window stop and an integral laterally extending web portion terminating in a gudgeon receiving portion adapted to overlie the path of the window sash and spaced

therefrom and having a suitably shaped bearing hole to receive the gudgeon of a shade roller, said base portion having a plurality of holes to receive securing means, one of the holes lying in the same plane as said bearing hole, and the entire bracket lying in substantially the same vertical plane, whereby the bracket may be first oscillated on said securing means across the inner face of the window stop and thereby swing the shade roller and web portion and its gudgeon-receiving portion into and out of the path of movement of the window sash to align the shade roller and then fixedly secured in alignment by securing means passing through another hole of the base portion so as to support the shade roller in the path of movement of the sash and to suspend the shade with its side edges in close proximity to the window stop, leaving practically no space between the side edges of the shade and casing for the passage of light around the edges of the shade.

In testimony whereof, I sign this specification.

DUANE A. PARKES.
